VISIBLE COIN SLOT MECHANISM

Arvid Dahlstrom and Peter N. Nelson, Chicago,
Ill., assignors to Developments Incorporated,
Chicago, Ill., a corporation of Illinois

Application January 2, 1935, Serial No. 52

10 Claims. (Cl. 194—98)

This invention relates to visible coin slot mechanism and more particularly to coin slot mechanisms adapted for use with vending machines and the like in which a movable member is arranged to receive a coin and the operation of the movable member will deposit the coin in a visible coin slot in which a plurality of preceding coins are displayed and from which a preceding coin is discharged with each operation.

The present invention may be built into and form an integral part of the vending machine if desired. However, the embodiment illustrated is particularly arranged to be manufactured as a unit or sub-assembly which may be attached to substantially any ordinary type of vending machine and which is arranged to cause movement of an operation controlling member of the slot machine when a suitable coin is inserted and the unit is operated.

It is an object of the present invention to provide a device which will be simple in construction, of few parts and which may be easily assembled to form a unit adaptable for use with various types of vending machines.

It is a further object to provide a visible coin slot mechanism in which certain types of slugs or coins, which are smaller than the normal coin for which the machine is designed, will be discharged through a suitable slug discharge chute. Also, if the coin opening is not filled by a proper coin, or if certain types of slugs are inserted, complete movement of the operating member cannot be made but the movement will be limited by suitable mechanism and the coin receiving member will be returned to its normal position instead of making the complete movement, thereby preventing the operation of the machine by slugs or coins not intended to permit the operation of the device.

It is a further object to provide a convenient device in which a slug or other article inserted in the device and which does not permit the operation thereof may be easily removed without injury to the machine and without disassembling any of the parts.

Another object is the provision of a visible coin slot mechanism in which suitable coins, consecutively inserted therein, permit the operation of the device and simultaneously deposit consecutive coins in a visible position from which they are consecutively discharged.

Further objects will be apparent from the specification and the appended claims.

In the drawings:

Figure 1 is a front elevation of one embodiment

of the invention which is arranged to be installed as a unit on any suitable vending machine.

Fig. 2 is a side elevation of the embodiment illustrated in Fig. 1 with a portion of the vending machine case and frame of the unit shown in section.

Fig. 3 is a top plan view of the embodiment illustrated in Fig. 2 with the vending machine case shown in section.

Fig. 4 is a detailed sectional view through the coin disk and support therefor with the disk-limiting pawl shown in side elevation. The view is taken on a line substantially corresponding to line 4—4 of Fig. 3.

Fig. 5 is a top plan view similar to Fig. 3 except that the cover is removed and the coin-receiving disk has been moved to its extreme position to deposit the coin in the so-called "visible coin slot or depression" and to move one of the preceding coins therefrom.

Fig. 6 is a longitudinal sectional view through the entire unit and taken on a line substantially corresponding to line 6—6 of Fig. 3, the coin disk being shown in its normal coin receiving position.

Fig. 7 is a top plan view of the outwardly extending disk supporting shelf with the disk removed therefrom.

Fig. 8 is an extended sectional detail view taken on a line substantially corresponding to line 8—8 of Fig. 5 and illustrates the slug discharge passage or chute and the depression under the disk arranged to receive consecutive coins with consecutive operations of the disk.

Fig. 9 is a detailed sectional view taken on a line substantially corresponding to line 9—9 of Fig. 5 and illustrates a coin discharge chute below the disk and arranged to receive consecutive coins discharged from the display depression or visible coin slot under the display opening in the disk and the display window in the cover.

Referring to the drawings in detail, the embodiment illustrated comprises a base or bracket-like support 1 which is provided with an outwardly extending disk-supporting shelf 2 and an inwardly extending shelf 3, the latter being arranged to operatively support a suitable mechanism for engagement with, and operation of, a vending control member within the vending machine case.

The outwardly extending shelf or disk-supporting portion 2 is provided with a cover 4 which may be secured on the shelf 2 by any suitable means, such as rivets 5. The entire frame work, therefore, comprises the supporting member 1 and the cover 4. The cover is secured to the

member 1 and the unit may be secured to the vending machine case by means of suitable bolts 6 extending through the oppositely disposed flanges of the base and cover. The cover 4 and the outwardly extending shelf portion 2 are arranged to provide a suitable space or pocket therebetween to snugly enclose an oscillatable coin-receiving disk 7 therebetween, this disk being pivoted for oscillation on a stud 8 which is secured in the outwardly extending shelf 2.

The disk 7 is provided with an outwardly extending handle 9 which, in the normal position illustrated in Fig. 3, rests against a shoulder 10 on the unit, and when moved to the position illustrated in Fig. 5, after the insertion of a coin in the disk, is limited in its movement by striking a shoulder 11.

When a good coin of the denomination for which the device is designed has been inserted, the handle 9 may be moved to the position shown in Fig. 5 and the mechanism of the vending machine will be operated during the latter part of this movement by the consequent inward movement of a plunger 12. This plunger 12 is slidably mounted on the inwardly extending shelf portion 3 by means of a slot 13 in which a suitable shouleder screw 14 is engaged. The plunger may be provided with a head 15 of any suitable shape for engaging with an operation controlling member within the vending machine such as a member 16 which is diagrammatically illustrated in Fig. 3. The opposite end of the plunger 12 is connected to a crank pin 17 on a pinion 18, the latter being rotatably mounted on the inwardly extending shelf 3 by means of a downwardly extending bearing stud 19 which extends through the shoulder and is provided with a disk 20 rigidly secured thereto. A coil spring 21 is mounted between the disk 20 and the shelf and one end 40 of the spring is engaged in a suitable hole in the disk and the opposite end is engaged with the shelf as illustrated in Fig. 6. The pinion 18 is in mesh with suitable gear teeth 22 on the coin disk 7 and the spring 21 therefore normally tends to hold all of the parts in the position illustrated in Fig. 3 and to return them to this position after they have been moved by the operator.

A pawl 23 is pivoted on the shelf 3 adjacent the pinion 18 and is normally retained in the position shown in Fig. 3 by means of a spring 24. A plurality of ratchet teeth 25 are provided on the pinion 18 and these teeth are arranged to cooperate with the pawl 23 after the coin disk 7 has been moved a certain predetermined distance from normal. This cooperation of the pawl 23 and ratchet teeth 25 prevents the return of the coin disk and mechanism associated therewith after the coin disk has been moved a predetermined distance.

As previously stated, the cover 4 completely covers the coin disk 7 and is provided with a coin receiving opening 26. A suitable coin or token may be inserted by laying it flat upon the cover as illustrated by dotted lines at 27 (Fig. 6) and then pushing the coin forwardly until it drops into a coin-receiving opening 28 in the coin disk 7. The coin disk 7 is substantially the same thickness as the coins intended to be used therein and the opening 28 is of such a size that the coin fits snugly therein but may easily drop therefrom.

In the embodiment illustrated, a rectangular opening 29 is provided under the coin-receiving aperture 28 in the disk 7 when the disk is in the normal position. This is to permit the easy re-

moval of slugs as will be described later. It will also be noted, by referring particularly to Figs. 1 and 5, that the support 1 is provided with a slug chute or discharge passage 30 on one side of the normal position of the coin aperture, and a coin discharge chute 31 is positioned on the opposite side. The slug discharge chute 30 is so arranged as to receive certain types of slugs or coins which are smaller than the coins normally intended to be used in the machine. These small coins or slugs of small diameter will be discharged through this slug passage 30 during a limited movement of the disk 7 and before the pawl 23 can cooperate with the ratchet teeth 25 to prevent the return of the disk. If a coin or token of proper diameter is used, it will pass over the slug discharge chute as the opening in the chute is somewhat smaller than the diameter of a proper coin.

If an attempt is made to operate the coin disk 20 without inserting a coin, or with certain types of slugs not filling the coin aperture, a spring pressed pawl 32 (Figs. 3 and 4) which is pivoted in the cover 4 will drop into the coin aperture 28 as the disk is moved and thereby prevent a complete movement of the disk, and when the handle 9 is released the disk will be returned to its normal position by the spring 21.

The upper end of the small coin and slug discharge chute 30 is shown by dotted lines in Fig. 5 and by full lines in Fig. 7. This opening is elongated but somewhat narrower than the diameter of a proper coin intended to be used in the machine and therefore when a proper coin is used it will ride over this opening during the movement of the disk, and as the pawl 32 cannot drop into the coin filled aperture 28, the disk will complete its movement to the position shown in Fig. 3 in which position the coin will drop into an arcuate depression or visible coin slot 33 which is formed in the outwardly extending shelf 2 and beneath the coin disk 7. This depression normally retains three coins therein as illustrated in Fig. 7, and during the movement of the disk with a good coin in the pocket 28, the coin slides over the top of the passage 30 and under the pawl 32 and the downwardly extending end 34 of a spring 35, which is secured in the disk 7, engages the first preceding coin in the depression 33 and moves all of the coins therein with the disk until the last coin is freed from a retaining spring 36 and drops into the coin discharge passage 31, which discharges the coin within the machine. During this movement of the coins in the depression 33, the coin which has been deposited in the disk aperture 28 will move to a position such as illustrated in Fig. 8 and will drop into the depression behind the preceding coins. The disk when released will then return to its normal position and another coin may be inserted. The pawl 32 (Fig. 4) is particularly intended to prevent the use of certain types of slugs having holes therethrough and also to prevent the operation of the device when no coin has been inserted.

It will be apparent that if a slug is inserted, which has a central opening therein, the pawl 32 will drop into this opening and prevent more than a very limited movement of the disk and the disk will return to its normal position with the slug remaining in the coin aperture. The rectangular opening 29 below the coin aperture is therefore for the purpose of inserting a finger or any suitable instrument, such as a pencil, upwardly through the coin pocket and pushing the

slug outwardly through the opening 26 in the cover. It will also be apparent that if a small coin or slug, which is smaller than the coin pocket, is inserted, the pawl 32 will drop downwardly and as the beveled edge 30 of the slug discharge chute is very close to the edge of the coin pocket, this small coin or slug may be discharged into the slug discharge chute 30. Should the small slug pass underneath the pawl 32, which is sometimes the case, it will still be discharged into the chute 30 as it is too narrow to ride thereover on the surface of the shelf 2.

The coin disk 7 is provided with an arcuate opening 37 which normally registers with the coin-receiving depression or visible coin slot 33, and a corresponding arcuate window 38 is provided in the cover so that the coins may be observed therethrough. The opening 37 in the disk is slightly narrower than the coins in the depression 33; therefore they are retained in the slot and cannot be misplaced by tilting the machine or by other means.

Those skilled in the art may vary the details of construction as well as the arrangement of parts without departing from the spirit of the invention. It is desired, therefore, that the invention be limited only by the prior art and the scope of the appended claims.

Having thus described the invention what is claimed and desired to be secured by Letters Patent is:

1. A coin controlled mechanism comprising a support having a coin exposing window, a coin-receiving plate movable back and forth in said support and having a coin-receiving aperture normally remote from said window and movable to a position adjacent said window, said support having a fixed coin slot immediately under said plate for supporting a plurality of coins visible through said window, said mechanism permitting successive coins inserted in said aperture to be moved into alignment between said window and said slot and deposited in said slot, coin controlled means to prevent effective movement of said plate unless a coin is inserted and means on said plate to progressively move the preceding coins in said slot to permit the deposit of the succeeding coins.

2. A visible coin slot mechanism comprising a base having a slug chute and a coin chute, an oscillatable disk on said base and having an aperture to receive a coin, means for oscillating said disk, means to limit the movement of said disk to a position where said aperture registers with said slug chute when said aperture is not filled with a proper coin, said limiting means being ineffective if a proper coin is used, said base being provided with a depression communicating with said coin chute to receive consecutive coins from said aperture when the coins are moved to align with the depression, and a resilient pawl on said disk for moving the coins in said depression with each effective movement of said disk whereby consecutive coins are deposited in said coin chute and the newly inserted coin is deposited in said depression, said disk having an opening therethrough whereby all of the coins in the depression are visible when the disk is in normal coin-receiving position.

3. In a coin slot mechanism, a support, an oscillatable disk in said support and having a coin-receiving aperture, means arranged to permit a limited movement only of said disk when the aperture is not closed by a proper coin and ineffective to limit the movement when said opening is closed, said support having a slug discharge pas-

sage adjacent one side of the normal position of said coin opening and a coin discharge passage adjacent the opposite side of said opening, said slug passage being positioned under the path of the coin opening and arranged to receive slugs or coins smaller than the opening during the limited movement of said disk, said support having a coin-receiving depression under said disk and arranged to receive a coin from said disk when said limiting means is ineffective, and means to engage preceding coins in said depression and to move said coins to discharge one coin with each complete movement of the disk.

4. A visible coin slot mechanism comprising a base having a slug chute and a coin chute, a rotary disk on said base and having an opening to receive a coin, means for rotating said disk, means to limit the movement of said disk to a position where said opening registers with said slug chute, if said opening is not completely filled with a coin, said limiting means being ineffective if the opening is completely filled, said base being provided with a depression to receive a plurality of consecutive coins from said opening, and ratchet means for moving said coins with each effective movement of said disk whereby consecutive coins are deposited in said coin chute and the newly inserted coin deposited in said depression, said disk having an opening therethrough whereby all of the coins are visible when the disk is in normal coin-receiving position.

5. A visible coin slot unit comprising a bracket arranged to be secured to a vending machine and having an outwardly extending shelf and an inwardly extending shelf, a cover for said outwardly extending shelf and having a coin receiving opening and an arcuate window, an oscillatable disk on said outwardly extending shelf and having a coin aperture normally registering with said cover opening and also having an arcuate aperture narrower than the diameter of a coin normally registering with said arcuate window, said unit having an arcuate coin slot under said disk and registering with said window and terminating in a coin chute, means for releasably retaining coins in said coin slot, a handle for moving said disk to deposit a coin from said coin aperture into the closed end of said coin slot, means on said disk to simultaneously move the coins in said coin slot to discharge one coin and to permit the coin in said disk to drop into said slot, means normally preventing movement of said disk and operative on the insertion of a coin to enable movement, and means on said inwardly extending shelf and movable by said disk to cause the operation of said vending machine.

6. A visible coin slot mechanism of the character described comprising a horizontal support, a horizontal pivoted disk enclosed therein and having an outwardly extending handle for oscillating said disk, said disk having a coin-receiving aperture and an oppositely disposed coin displaying aperture, a window over said display aperture, said support having a closed end coin slot under said display aperture and said window and terminating in a coin discharge opening, said support having a slug discharge opening between the closed end of said slot and the normal position of said coin-receiving aperture, means to limit the movement of said disk to discharge slugs or coins smaller than said coin receiving aperture into said slug discharge opening and to permit proper coins to drop into the closed end of said coin slot, and means carried by said disk to move all the coins in said slot to discharge the first preceding coin

and receive the last succeeding coin, said support having a coin-receiving opening communicating with said disk coin aperture when in normal position and an opening underneath said coin aperture whereby a coin or slug therein may be pushed outwardly from the disk.

7. A coin slot unit comprising a substantially flat base plate having means intermediate its ends for securing the unit to the wall of a slot machine whereby a portion extends outwardly and a portion inwardly of said wall, an oscillatable coin disk pivoted on the outer portion of said plate and having means for limited manual movement thereof, a cover cooperating with said base to form a closely fitting pocket for said disk and having a coin aperture therein, said disk being not materially thicker than a coin and having a coin aperture normally positioned to receive a coin from said cover aperture, an arcuate window in said cover, said base having an arcuate coin groove under said disk in alignment with said window, said disk having an opening normally positioned to expose coins in said groove, a coin chute to discharge consecutive coins from said groove, means controlled by the movement of said disk to move the coins in said groove sufficiently to receive a succeeding coin, means preventing effective movement of said disk except upon insertion of a coin, means movable by said disk for controlling the operation of a slot machine, and resilient means to return said disk to normal position after operation.

8. A coin slot unit comprising a bracket for attachment to a slot machine and having a coin-receiving aperture and a horizontal pocket not substantially greater than the thickness of a coin, a disk in said pocket and having a handle extending through a slot in said bracket for limited rotary movement of said disk, said disk having a coin aperture normally positioned to receive coins from said bracket aperture, a support having a coin groove under said disk to receive consecutive coins therefrom when said disk is operated, one end of said groove communicating with a passage extending through the inner face of said bracket, means controlled by the movement of said disk to discharge consecutive coins from said groove,

means normally preventing effective movement of said disk and coin controlled to enable effective movement to deliver consecutive coins from said disk to said groove, a second pivoted disk for controlling the operation of a slot machine and having segment teeth cooperating with segment teeth on said coin disk, means cooperating with said second disk to necessitate the complete effective movement of said coin disk, and resilient means for returning the coin disk to normal position.

9. A coin slot unit for application to various types of coin controlled machines, comprising a base arranged to be secured to the outside of a case and having a portion extending through the wall thereof, said base forming a support, operating members on said support in substantially a single plane, said operating members comprising a manually movable disk, and means cooperating with said disk to cause the operation of the coin controlled machine, a cover for said disk, said disk having a coin aperture, said cover having an aperture whereby a coin may be inserted into said disk aperture, and means to prevent the effective operation of said disk when a coin is not inserted and to enable operation when a coin is inserted.

10. A coin slot unit comprising a bracket having a horizontal pocket to receive an oscillatable coin disk, a coin disk pivoted in said pocket and having a coin aperture, a handle on said disk and extending through a slot in said bracket for limited movement of said disk, a horizontal coin-receiving support on said bracket substantially in axial alignment with said disk and having an associated passage to deliver a coin to said disk, said coin disk aperture being normally on the substantially vertical axial plane of said bracket, a support having a coin groove below said disk and out of alignment with said disk aperture and arranged to receive a coin with each effective operation, said groove communicating with a passage for delivering coins therefrom, means normally preventing operation of said disk and coin controlled to enable operation, and means to move the coins in said groove with each effective operation to enable the delivery of a succeeding coin from said disk.

ARVID DAHLSTROM.
PETER N. NELSON.
